UNITED STATES PATENT OFFICE.

MARCEL ACHILLE VIOLET, OF PANTIN, FRANCE.

TWO-STROKE INTERNAL-COMBUSTION ENGINE.

Application filed June 14, 1921, Serial No. 477,528, and in France June 16, 1920.

The invention relates to a motor comprising an even number of cylinders, two in number or in groups of two, and of which each element formed by a pair of cylinders possesses a casing or a compartment of a casing, which is tight and does not communicate with an adjacent casing.

This motor is illustrated in the accompanying drawing.

10 Fig. 1 is a vertical section in a plane passing through the axis of the two cylinders.

Figs. 2 and 3 are vertical sections taken respectively transverse of the axis of the two cylinders.

15 The two parallel cylinders A and B are united by a common explosion chamber *a*, the cylinder A being provided with exhaust ports *b*, which are controlled by the piston *c* when it is at the lower end of its 20 stroke and which then places the cylinder in communication with the atmosphere. The cylinder B is provided with enlargements *d* formed in its wall and having the object to place the lower part of this cylinder in communication with the upper part, when its piston *c'* is at the bottom of its 25 stroke, the gases passing through these enlargements and through the openings *e* formed in the wall of the piston.

30 At the lower part of the two cylinders, other ports *f*, *f* are in communication with a hollow rotary valve *g* connected by its open end with the carburetter. This valve, actuated by any suitable mechanism, such as 35 by means of a chain *n* for example, rotates at the speed of the motor and, by means of suitably disposed openings, places the carburetter in communication with the lower part of the cylinders during the return 40 stroke of the pistons.

The tight casing *h* contains a crank shaft actuating two connecting rods *i*, *i*, upon a single crank pin *j*. Two fly wheels *k* at the extremities and a central fly wheel *l* fill the 45 casing in as complete a manner as possible.

The operation of the motor is as follows:

The two pistons being at the lower end of the stroke, if the motor is turned by 50 hand, they reascend creating a vacuum in the space below the pistons, which is filled by the gases drawn in through the carburetter and the valve, which is open during the ascent of the pistons. At this moment, 55 the pistons have at the upper part compressed the gases resulting from a preced-

ing cycle, the spark issues from the plug *m*, the explosion occurs and the pistons commence their descent, compressing the gases admitted by the valve, which was reclosed 60 when the pistons were at the top of their stroke.

In descending, the piston *c* uncovers the ports *b* of the cylinder A; exhaust occurs; then piston *c'* opens the enlargements *d* of 65 the cylinder B; the compressed gases beneath the pistons pass from the lower part of both cylinders to the upper part of cylinder B and into cylinder A. The pistons, in reascending, close the ports *b* and *d*, compress the fresh gases admitted, drawing in another charge into the casing, and the cycle 70 recommences.

What I claim as my invention, and desire to secure by Letters Patent, is:—

75 1. A two-stroke internal combustion engine, comprising a pair of parallel cylinders connected together at their heads and forming a common explosion chamber, a closed crank case common to both cylinders, driving pistons in said cylinders, a hollow, rotary, fuel-controlling member, ports at the lower end of one of the cylinders through which fuel is supplied to the crank case from said member, said ports controlled by one of said pistons, inlet ports in one cylinder and exhaust ports in the other cylinder controlled by the respective pistons, and a by-pass connecting the crank case through the interior 80 of one of the pistons with said inlet ports.

85 2. A two-stroke internal combustion engine, comprising a pair of cylinders connected together at their heads and forming a common explosion chamber, a closed crank case common to both cylinders, driving pistons in said cylinders, a hollow, rotary, fuel-controlling member, ports at the lower ends of 90 one of the cylinders through which fuel is supplied to the crank case from said member, said ports controlled by one of said pistons, inlet ports in one cylinder and exhaust ports in the other cylinder controlled by the respective pistons, the exhaust ports being arranged to open in advance of the inlet ports, 95

100 by-passes connecting the crank case and inlet ports through the interior of one piston and controlled at both ends thereby, a crank, and connecting rods for the pistons connected to said crank.

105 In testimony that I claim the foregoing as my invention, I have signed my name.

MARCEL ACHILLE VIOLET.
